HEAT TREATING APPARATUS

Howard E. Somes, Detroit, Mich., assignor to
Budd Induction Heating, Inc., Philadelphia,
Pa., a corporation of Michigan

Original application January 21, 1937, Serial No.
121,598, now Patent No. 2,208,607, dated July 23,
1940. Divided and this application July 22,
1940, Serial No. 346,812

11 Claims. (Cl. 219—13)

This application is a division of my application Serial No. 121,598, filed January 21, 1937, now Patent No. 2,208,607, dated July 23, 1940, for Apparatus for heat-treating gun bores.

The title of this invention indicates the class to which it belongs. The figures of the drawings following show one embodiment of my invention. As usual it is susceptible of many others.

Fig. 1 is a vertical side elevation of the apparatus.

Fig. 2 is a front elevation at right angles to Fig. 1.

Fig. 3 is a transverse cross section of the vertical framework of the apparatus.

Fig. 4 is a plan view of the lower bracket arm.

Fig. 5 is a plan view of the end of the supporting arm.

Fig. 6 is a plan view at the top of the base block supporting the work.

Fig. 7 is a side view in vertical axial section of the switching transformer and tool carriage, on an enlarged scale, said view being of that portion of the apparatus contained within the dotted rectangle 7 of Fig. 1.

Fig. 8 is a fragmentary enlarged view of the upper end of the machine contained within the dotted rectangle 8 of Fig. 1.

Fig. 9 is a fragmentary enlarged view of the lower end of the machine contained within the dotted rectangle 9 of Fig. 1.

Fig. 10 is a transverse section of the quenching mechanism feed on line 5—5 of Fig. 1.

Fig. 11 is a detail of the quenching spray head.

Fig. 12 is a longitudinal sectional view of a gun treated in accordance with the invention.

The central object of the invention is the achievement of an apparatus whereby the bore of a gun can be heat treated by high frequency induction. So far as I am aware this has never been achieved prior to my invention.

According to my invention there is generated in one axial region of the bore annular heating currents in and near the surface of the bore and of a determinate axial extent, progressively shift the currents so generated axially of the bore to circulate through successive axial portions of the bore, and as the currents are so shifted, quench the heat which has been generated by the currents so circulated and shifted. Preferably I uniformly progress the axially shifting currents which achieve the heating, and uniformly progress the quench of those heated portions from which the current has been shifted. Preferably during the process of shifting I maintain a determinate axial spaced relation between the zone

traversed by the currents and the zone subjected to the following quench so that the zone of the bore which has been heated fully to quenching temperature will precede this space. From another angle it may be said that I prefer to maintain between the zone traversed by the progressing induced current and the zone being quenched a zone which has been heated to quenching temperature by the axial shifted current but momentarily free from substantial influence of either the shifting current or the quench. Preferably I begin the inducing of the treating current outside of the barrel and of an intensity and volume approximating that which shall be generated within the barrel and similarly end the inducing of current of similar intensity and volume at the opposite end of the gun, also outside of the barrel. The current, the inducing of which has so begun and so ended, is progressively shifted in the one case into one end of the barrel, and after being progressed throughout the extent of the bore is similarly shifted out of the opposite end thereof.

The apparatus comprises means to support the gun with free space substantially equal to its length disposed axially beyond each end thereof and freely accessible from the end. In the free space at one end is a mechanism for progressing into along, back along and again out of the bore of the gun a high-frequency induction work coil of a dimension adapted to induce in the surface of the bore and in proper proximity thereto, the heating currents desired. Occupying the space at the opposite end of the gun is a mechanism for introducing to the bore progressing therewith, back therewith and then out again, a quenching head through which quenching fluid may be projected upon the heated bore to be quenched. Coordinated motor driving devices for these two devices, and a spacing mechanism between the high frequency induction work coil and the quenching head insure their coordinated traverse of the bore of the gun from one end to the other in proper spaced relation. A chronometrically driven controller insures a coordinated activity of the various parts of these devices in their functional relations to each other individually and collectively. A means to introduce a dry inert gas under pressure to the bore being treated and progressing it under pressure between the high frequency induction coil and the bore and counteracted to the flow of the quenching medium prevents vaporized and sprayed quenching medium and other moistures from engaging upon the

heated surfaces of the bore and thereby attains its treatment without marring its surfaces, either through oxidation, de-carbonizing or through electrical faults brought about by the excess presence of moisture.

Referring then to the drawings, 10 is the gun, 11 designates three vertical columns or standards of the main frame of the apparatus, and founded upon the floor 12 of the shop, or other platform upon which the equipment is to be used. The gun points vertically upward and at its end which is at the floor 12 is seated and centered upon a flanged centering ring 13 borne upon the head of a base block 14 appropriately anchored as by bolts 15 to the foundation of the floor. It is retained in place against axial displacement not only by the flange 16 of the plate 13, but also by an encircling clamping block 17 which is made in two halves hinged together at 18 and clamped together and about the gun through the swinging link pin 19 engaging its opposite side in a well known manner.

The standards 11 of the main frame of the machine are anchored to the concrete floor or other platform 12 in any suitable manner and projecting vertically upward. They support the upper end of the gun 10 by means of a laterally projecting arm 20, which arm is vertically adjustable up and down the reduced cross section 21 of the standard 11 and clamped in any adjusted position by means of the bolts 22 which connect together the halves which embrace the shaft 21. The end which engages the muzzle of the gun 10 is also made in two halves, as indicated at 23, the one of which is integral with the arm 20 and the other swingable about the pivot 24 to engage and center the upper end of the gun through the V-shaped jaws 25 and thereafter be clamped firmly thereupon by the link pin 26 connecting together the opposite ends of the halves from the pivot 24. Between the floor level 12 and this arm 20 supporting, aligning, centering and clamping the upper end of the gun is located a transverse inter-column brace member 27 for the three columns 11. Such a brace is located also at the extreme upper end, it will be seen, and as many of these inter-column braces may be utilized at different points as it may prove expedient to use. Each of these comprises a generally triangular main body, one apex of which, 28, is made in halves and fixedly clamped about the central column 11 and the two other apices of which are made in halves bridged by a common hinged bridging member 29 pivoted by a hinge 30 to the main body 27 and coupled to the main body at the end opposite the hinge 30 by means of the link pin coupler 31. These members 27 engage shoulders 32 respectively upon the columns. They do not engage the barrel of the gun. Instead, the main body is provided with an opening 33 concentric with the axis of the gun and large enough for the barrel to pass freely therethrough. If desired, however, adapters may be placed in this opening of sufficient size to engage the barrel and be clamped about it by the bridging member 29 when the members 27 are arranged in place. The opening of the bracing members 27 through the swinging of the bridging member 29 enables the guns to be placed in the apparatus and removed therefrom without disassembly of the apparatus and to be placed in position laterally rather than raised or lowered vertically into position.

On the upper portion of the main frame col-

umn 11 are mounted upper and lower swingable bracket arms 34 and 35, at opposite ends of a spacing sleeve 36, the upper bracket arm 34 being mounted upon the reduced upper portion 5 of the main frame column 11 and arranged to be clamped in position thereon against shoulder 37 by means of a clamping nut 38, while the lower bracket arm 35 is split where it surrounds the column and arranged to be clamped thereon by means of suitable clamp bolts 39. The swinging bracket arms 34 and 35 form a support for the tool carriage 40 which it supports on a rotatable feed screw shaft 41 journaled at opposite ends in the upper and lower bracket arms 34 and 35 by means of suitable ball bearing journals 42 and 43 respectively, the screw shaft 41 being arranged to be rotated by means of a bevel gear 44 secured at its upper end by means of a suitable key 45 and driven by a complementary bevel gear 46 carried at the end of the shaft of the motor 47 mounted upon the top of the upper bracket arm 34.

The screw shaft 41 is in driving engagement with the tool carriage 40 through the internal threaded portion 48 of the carriage through which it passes for elevating and lowering the carriage according to the direction of rotation of the screw shaft. The bracket 49 mounted on the carriage 40 carries the heating coil supporting rod 66 and a motor cylinder 50 which movably supports the casing 51 of a switching transformer.

The transformer casing 51 is supported for definite limited movement by the work cylinder 35 50 relative to the rod 66 by means of the tubular piston rod 52 carried by the piston 53 fitted in the work cylinder about the rod 66. The transformer casing comprising upper and lower portions 54—55 is provided in its lower portion with a cylindrical transformer primary element 56 comprising a cylindrical laminated core element 57 carrying nested within its inner cylindrical surface the primary transformer winding 58 whose terminals 59—60 extend outwardly through the transformer casing for connection with a suitable source of alternating current, not shown. Mounted within the transformer casing 51 is the secondary transformer element 62 comprised in general of the secondary transformer winding 63 imbedded in the outer surface portion of a hollow laminated core element 64, the whole assembled between end plates 65 and carried upon the hollow vertical slide rod 66 in fixed relation therewith so that when the piston 53 of the work cylinder 50 is moved to its lowermost position in the cylinder, the secondary transformer element 62 will remain stationary while the transformer casing 51 will move downwardly relative thereto. This relative movement will bring the primary transformer element 56 and with it the primary winding 58 down over the laminated core extension 61, the latter providing a low reluctance core element for the primary winding.

65 The hollow rod 66 is held fixed in relation to the cylinder 50 and bracket 49 at its upper end by means of the shouldered portion 67 and the nut 68, the transformer casing 51 having sliding bearing on the rod 66 through the tubular piston rod 52.

The hollow rod 66 has sliding bearing in the bushing 69 in the bracket 35 through which bushing it extends down into and through the barrel of the gun 10 to the breech end where it carries 75 the inductive heating coil 70 which in its present

lowermost position is situated outside the breech within a lower terminal chamber 71 in the base block 14.

Circuit connection between the winding 63 of the transformer secondary element and the heating coil 70 is effected by means of the secondary terminals 72 and tubular conductors 73 which extend down through the hollow tube 66 to the terminals of the heating coil 70. Cooling water is circulated through the tubular conductors 73 for supply of cooling liquid to the transformer secondary coil and the heating coil 70 by means of the upper extensions of the tubes 73 which extend up through the hollow tube above the bracket 49 as indicated at 74 where they may be connected with any suitable source of supply of cooling fluid not shown.

The chamber 71 is formed with an internal diameter the same as that of the bore of the gun and is lined with a radially laminated wall 75 extending up to form a laminated lining or protecting sleeve 76 for the threaded portion of the gunbreech. The function of this laminated lining is to provide a low impedance magnetic circuit for the heating coil 70 for a purpose to be hereinafter explained in connection with the description of operation.

Like the secondary transformer element 62 the heating coil 70 is formed of a hollow conductor carried upon a cylindrical radially laminated core element 77, but with an outside diameter proportioned to pass freely through the barrel of the gun out of contact therewith and in close proximity to the surface of the bore.

At the muzzle of the gun 10 I provide an upper terminal chamber 78 similar to the lower terminal chamber 75 and like the chamber 75 provided with a radially laminated lining or wall 79, so positioned and proportioned as to receive and surround the heating coil 70 when the latter is drawn up thereinto, to provide a low reluctance magnetic circuit for the coil. The chamber 78 is hermetically sealed to the muzzle of the gun 10 by means of the gasket element 80 fitted between the lower opening of the chamber and the muzzle of the gun, and a stuffing box 81 at the top of the chamber for the hollow rod 66. Pressure control valve 82 connected with the upper end of the terminal chamber 78 provides for the introduction of a dry inert gas under pressure from a suitable source not shown, whereby the chamber 78 and the gun barrel 10 may be maintained filled with an inert gas under pressure, the gas passing on down through the clearance between the heating coil 70 and the bore of the gun into the lower terminal chamber 71 to an outlet conduit 83 which latter provides an outlet permitting complete displacement of air or other undesirable substance from the gun bore by the inert gas.

A lower extension 84 of the bottom terminal chamber 71 extends down through the supporting floor 12 into communication with a quenching fluid exhaust chamber 85. Through this chamber a sliding quench-tube 86 passes up into the lower extension 84 of the lower terminal where the tube carries a quenching head 87 spaced from and substantially sealed off from the heating coil 70 by means of a piston head 88 and center projection 89 fitting into the open end of the hollow core of the heating coil 70. The tubular rod 86 enters the exhaust chamber 85 through suitable stuffing box 90 and is mounted for vertical movement to progress the quenching head 87 up through the lower terminal chamber

71 into and through the bore of the gun to the upper or muzzle end of the gun, and to thereafter retract the quenching head back to its lowermost position shown in Fig. 9 of the drawings.

- 5 Movement of the quenching head is properly coordinated with the movement of the heating coil 70 to follow the upward movement of the heating coil through the gun barrel in constant spaced relation to the coil as determined by spacing piston or closure element 88. In the present embodiment this coordinated movement of the quenching head is effected by means of a driving motor 91 operating through a pinion 92 and vertically sliding rack element 93 carrying bracket 94 to which the lower end of the tube 86 is fixed. The driving motor is adapted to exert sufficient lift on the tube 86 to cause it to follow the heating head upwardly through the gun barrel and without undue upward pressure on the heating coil. A stationary brace and guide element for the rack 93 extends vertically between the floor support 12 and a lower stationary bracket support 96. The quenching fluid is supplied to the tubular rod 86 by means of a flexible hose connection 97 at the lower end of the tube. Exhaust quenching fluid is drawn off from the exhaust chamber 85 through the outlet conduit 98 and pressure valve 99 and a trap or gas and liquid separator 100 for separating such of the inert gas as may pass downwardly into the exhaust chamber 85.

Operation of the pneumatic motor cylinder 50 is controlled through an electro-magnetically operated control valve 101 and piston valve 102 35 operable in known manner upon energization to exhaust the top of the cylinder 50 and admit air to the bottom thereof to raise the piston 52 to the top of the cylinder and upon deenergization to exhaust the lower end of the cylinder and 40 admit air to the upper end to effect downward movement of the piston thus operating upon energization to raise the transformer shell 51 into the position shown and upon deenergization to effect lowering of the transformer shell to move the primary winding 63 out of cooperative relation with the secondary winding 64 and into cooperative relation with the low reluctance magnetic circuit element 61.

Reference may be had to my Patent 2,208,607, 50 aforesaid, in which I have shown and described a suitable control system and chronologically driven controller for controlling the operation of the various mechanisms in desired sequence.

In operation, assuming that a gun to be operated upon is in position in the machine as shown in the several drawings, with the upper terminal chamber 78 in place on the muzzle of the gun 10 in sealed relation thereto, the heating coil element 70 in the raised position and wholly within the upper terminal chamber, and the quench head 87 in the lowermost position as shown in the several views, the operator starts the machine in operation. First, the motor 47 operates to move the heating coil 70 downwardly from the upper terminal chamber 78 through the bore of the gun and into the lower terminal 71 as indicated in Figure 9 of the drawings. Immediately after the heating coil 70 starts its downward movement, the control valve 82 is connected to a suitable supply of dry inert gas. The dry gas thus enters the upper terminal chamber 78 as the heating coil leaves this chamber, following the coil down and continuing to fill and maintain the bore of the gun filled under suitable pressure during the downward movement of

the coil and continuing after the heating coil reaches its lowermost position, the gas escaping through the clearance between the heating coil and the sides of the lower terminal chamber and out through the vent conduit 83. Any suitable means may be provided for causing the heating coil to come to rest in the lower position shown in Fig. 9 without undue strain on the mechanism, as by providing the motor 47 in the form of a constant torque motor or by providing a suitable slip clutch connecting between the motor and the drive screw 41 or by the provision of suitable resilient or elastic lost-motion means.

The primary winding 56 of the switching transformer is next connected with its source of high frequency current. At substantially the same time quenching medium is supplied through hose connection 97 to the quench-head 87, and the electromagnetic valve is energized to admit air to the lower end of motor cylinder 50, raising the transformer shell and with it the primary transformer winding 56 into transformer coupling relation with the secondary winding 62, thus energizing the heating coil 70 through the conductors 73. With the heating coil thus energized and the quench-head operating to discharge quenching medium outwardly in the space surrounding the quenching head below the heating coil, the motors 47 and 91 are operated in a direction to move both the coil 70 and the quench head 87 upwardly through the bore of the gun, the quench head trailing the coil until the coil enters and comes to rest in the upper terminal chamber 78, at which time the motors are de-energized. The motors 47 and 91 are so timed in operation that they move through the gun bore at the constant rate required to effect the proper heating and quenching, the quench head always abutting the lower end of the coil 70 through the piston diaphragm 88.

Upon entrance of the coil 70 into the chamber 78, the supply of gas to valve 82 is cut off and the valve 101 is operated to operate the primary winding of the transformer to uncoupled position, thus deenergizing the coil 70. After this the supply of quenching medium is cut off and the motor 91 reversed to move the quench head back to its original position.

The gun thus heat-treated is free to be removed from the machine.

A gun so treated is shown in Fig. 12 of the drawings where the heat-treated portion near and including the inner surface of the bore is indicated at 129.

During upward movement of the heating coil 70 closely followed by the quenching head 87, quenching fluid is kept out of contact with the coil or the clearance space between the coil and the bore of the gun by means of the separating piston member 88, leakage of quenching fluid beyond the piston through the slight clearance between the piston and the walls of the gun bore being prevented by the presence of the inert gas under pressure in the spaces above the quenching head and by the downward passage of such gas through the clearance between the separating piston 88 and the walls of the gun bore. Any gas passing out through the quenching fluid outlet conduit 48, (where a liquid quenching fluid is used) may be separated off from the liquid by the liquid trap 101 (Fig. 1).

Inasmuch as the heating coil 70 is initially energized for its upward movement through the barrel of the gun before entering the breech of the gun and is maintained energized after leav-

ing the muzzle to insure an even treatment of the gun barrel throughout its length, it is desirable to maintain the electrical characteristics of the heating coil substantially constant during such movement and during its complete time of energization. This is to insure that the energy output of the coil will remain substantially constant throughout its passage through the gun barrel and during its energization while outside of the gun barrel in either the upper or lower terminal chambers, and it is for this purpose that the low reluctance laminated inner wall* or linings 79 and 75 are provided for the upper and lower terminal chambers 78 and 71, respectively. Preferably such low reluctance elements are arranged to maintain the inductive reaction of the heating coil 70 substantially constant throughout its travel from the lower terminal chamber to the upper terminal chamber, or otherwise affect such reactance to prevent undesirable change in power factor due to removal of the coil from the surrounding low reluctance material of the gun.

While I have herein shown and described a preferred embodiment of my invention for the sake of disclosure, it is to be understood that the invention is not limited to the specific embodiment shown and described, but contemplates all such variants and modifications thereof as fall fairly within the scope of the appended claims.

What is claimed is:

1. Apparatus for heat treating an elongated hollow cylindrical object at and near the inner surface, comprising means for holding the object to be treated, a transformer having relatively movable primary and secondary windings, an induction heating element electrically connected with the secondary winding for energization thereby, means for moving the heating element and the complete transformer as a unit relative to the holding means to move the heating element through the hollow object, and means for moving the primary winding into and out of transformer coupling relation with the secondary winding independently of the relative movement between the heating element and the said holding means.

2. Apparatus for heat treating elongated objects comprising a plurality of spaced columns, spaced object-supporting members associated with said columns for holding the objects to be treated relative to said columns, an induction heating element, supporting means for said heating element having a pivotal connection with one of said columns, said heating element being supported by said supporting means and being movable relative thereto for movement relative to at least a portion of the object adapted to be heated thereby, a power means for moving said heating element longitudinally of the object to be treated, said supporting means being movable about its pivotal connection with said one column to dispose said heating element out of operative alignment with respect to the object adapted to be heated.

3. Apparatus for heat treating elongated objects comprising a frame, supporting means for elongated objects to be heat treated, a heating coil having an arbor, said heating coil and arbor being movable longitudinally relative to a surface of the object to be heat treated for progressive heat treatment of such object, means on said frame for supporting and guiding said arbor during movement of said arbor and coil, a transformer carried by said arbor for movement therewith, said transformer having a secondary coil

electrically connected with said heating coil, and means for longitudinally moving said arbor.

4. In an apparatus for heat treating elongated objects comprising a frame, support means for an object, a heat treating coil, an arbor secured to said coil, guide means secured to said frame slidably receiving said arbor, a switching transformer mounted upon said arbor and having a secondary coil secured to said arbor and connected directly to said treating coil, and a primary coil adapted to be moved into and out of inductive relation with said secondary coil, means to support said primary coil slidably upon said arbor, motor means for shifting said coil support means to move said primary coil into and out of inductive relation with the secondary coil, and power means for effecting relative movement between said arbor and said frame.

5. In an apparatus for heat treating elongated objects a stationary guide, an arbor slidable in said guide and having a heating coil on one end thereof, and a transformer secondary coil secured thereon on the other side of said guide, a housing over said secondary and slidable on said arbor, and having a primary winding therein adapted to be moved into and out of inductive relation with said secondary, a cylinder mounted upon said arbor, a piston therein slidable upon said arbor and having a piston rod projecting from one end of the cylinder and secured to said housing, a guide on the end of said arbor, and a rod extending parallel with said arbor adapted to slidably engage said last named guide.

6. In an apparatus for heat treating elongated objects a stationary guide, an arbor slidable in said guide and having a heating coil on one end thereof, and a transformer secondary coil secured thereon on the other side of said guide, a housing over said secondary and slidable on said arbor, and having a primary winding therein adapted to be moved into and out of inductive relation with said secondary, a cylinder mounted upon said arbor, a piston therein slidable upon said arbor and having a piston rod projecting from one end of the cylinder and secured to said housing, a guide on the end of said arbor, a rod extending parallel with said arbor adapted to slidably engage said last named guide, said guide and rod having screw threaded engagement and means for rotating the rod to effect movement of said arbor.

7. In an apparatus for heat treating objects, a frame, supporting means for the object to be heated, a heat treating coil, an arbor secured to said coil, guiding means on said frame for guiding said arbor for coaxial movement, a switching transformer coaxially mounted on said arbor for bodily movement with said arbor and having a primary winding and a secondary winding, said windings being relatively movable coaxially, one of said windings being fixed on said arbor, means for axially moving the other winding relative to said one winding, said secondary

winding being electrically connected to said coil, and means for axially moving said arbor relative to said guiding means and the object to be heated by said coil.

8. In an apparatus for heat treating a metallic object, supporting means for the object to be heat treated, a fixed guide, an arbor axially slidably in said guide, a heating coil secured to said arbor, a transformer secondary coil secured to said arbor in axially spaced relation with and electrically connected to said heating coil, a transformer primary coil, a housing for said primary coil slidably supported on said arbor, motive means for sliding said housing on said arbor to move said primary coil into and out of transformer relation with said secondary coil, and means for axially moving said arbor relative to said guide and the object to be heat treated.

9. In a heat treating apparatus for hollow objects, a work support for holding the object to be heat treated, a reciprocable arbor of tubular construction, guiding means for guiding said arbor axially with respect to the hollow of the object to be heat treated, a heating coil attached to one end of said arbor, said coil being hollow for conducting coolant therethrough, electrical and coolant connections for said coil extending longitudinally within the hollow of said arbor, and means for moving said arbor to position said coil into inductive heating relation with the surface of the hollow of the object to be heat treated.

10. In an apparatus for heat treating elongated objects, a stationary guide, an arbor axially slidably in said guide, a heating coil secured to said arbor, a switching transformer having relatively movable primary and secondary windings carried by said arbor, one of said windings being fixed to said arbor and the other of said windings being slidable relative to said arbor, a support for said arbor fixed thereto, means carried by said support for sliding said other winding relative to said arbor and first winding, and means for sliding said arbor and support relative to said guide means.

11. In an apparatus for heat treating elongated objects, a stationary guide, an arbor axially slidably in said guide, a heating coil secured to said arbor, a switching transformer having relatively movable primary and secondary windings carried by said arbor, one of said windings being fixed to said arbor and the other of said windings being slidable relative to said arbor, a support for said arbor fixed thereto, means carried by said support for sliding said other winding relative to said arbor and first winding, and means for sliding said arbor and support relative to said guide means, said sliding means comprising a screw rotatably journaled in said guide means against axial movement relative thereto and being threadably engaged with said support, together with means for rotating said screw.

HOWARD E. SOMES.
